United States Patent Office.

E. A. GOODES, OF PHILADELPHIA, PENNSYLVANIA, ASSIGNOR TO HIMSELF,
E. L. MILLER, AND W. H. MORFORD, OF SAME PLACE.

Letters Patent No. 70,831, dated November 12, 1867.

METAMORPHOSCOPE.

The Schedule referred to in these Letters Patent and making part of the same.

TO ALL WHOM IT MAY CONCERN:

Be it known that I, E. A. GOODES, of Philadelphia, in the county of Philadelphia, and State of Pennsylvania, have invented a new and improved Apparatus for Exhibiting Metamorphoses of Figures and Pictures; and I do hereby declare that the following is a full, clear, and exact description of the same, reference being had to the accompanying drawing, making a portion of this specification, in which—

Figure 1 is a perspective view of an apparatus constructed according to my invention.

Figure 2 is a plan view of the same, with the cover or top plate removed.

Figure 3 is a vertical longitudinal section of the same.

Similar letters of reference indicate corresponding parts in all the figures.

This invention, which I term a metamorphoscope, designed for the amusement of children and others, consists in two or more endless aprons of different lengths, provided with sections of figures or pictures, and so combined, that when simultaneously operated, the position of the sections upon one belt will be changed with reference to those upon the others, in such manner that the figures or pictures will be successively formed by the conjunction of different sections, thereby enabling a variety of such figures or pictures to be produced, proportioned to the number of combinations of which the sections upon the belts are capable.

To enable others to understand the construction and operation of my invention, I will proceed to describe it with reference to the drawings.

A, B, and C represent three endless belts, which are made of different lengths, as shown in figs. 2 and 3. These belts are supported at one end by a transverse roller, A*, at their opposite ends by separate rollers marked respectively, a, b, and c. These rollers are supported by narrow longitudinal bars a*, and are made preferably of rectangular form, as shown in fig. 3. The belts with their several rollers are situated within a suitable box or frame, D, and the shaft or axle d of the roller A*, extends through one side of such box, and is furnished with a milled head or knob, c', by turning which, the said roller may be rotated in such manner as to simultaneously move the endless belts at a uniform speed. The top plate or cover e of the box D, which is placed over the endless belts, is furnished with a transverse hole or opening, f, through which the figures or pictures, provided as hereinbefore fully set forth, upon the belts, may be viewed as the said figures are brought underneath the same by the movements of the aforesaid belts. Provided upon each of the belts, at equal distances apart, are a number of sections or portions of pictorial representations, which, as represented in the drawings, may be those of human figures, the sections upon each belt being those of corresponding parts of the figures. Thus, those upon the belt A represent the head of a human figure, while those of the belts B C indicate respectively the body and lower extremities of the same; and inasmuch as the belts are of different lengths, and are provided with different numbers of sections, it follows that when the said belts are moved by means of the knob c', as hereinbefore explained, the sections upon each of the belts, instead of being kept in the same position with reference to those of the others, will be moved or changed with regard thereto, new figures being formed by new combinations of the sections newly brought into line with each other, so that by these means the figures may be changed or metamorphosed a number of times, proportioned to the number of combinations of which the different sections of the several belts are capable. The pictorial representations, instead of representing individual figures, as hereinbefore described, may, when desired, be those of groups or landscapes.

What I claim as my invention, and desire to secure by Letters Patent, is—

1. The combination of two or more endless belts of different lengths, furnished with sections of figures or pictures, substantially as and for the purpose specified.
2. The combination of the endless belts furnished with sections of figures or pictures, the rollers A* a b c, and the top plate or cover e, formed with an opening, f, substantially as and for the purpose specified.

E. A. GOODES.
